ATTORNEY

UNITED STATES PATENT OFFICE

NEVILLE BYLAND DAVIS, OF SALE, ENGLAND, ASSIGNOR TO WESTINGHOUSE ELECTRIC & MANUFACTURING COMPANY, A CORPORATION OF PENNSYLVANIA

INDUCTION FURNACE

Application filed January 8, 1930, Serial No. 419,436, and in Great Britain January 8, 1929.

My invention relates to electric furnaces and more particularly to electric-induction furnaces.

It is one of the main objects of my invention 5 to provide a novel means for, and a method of, drying out the lining of an electric-induction furnace.

Another object of my invention is to provide a means permitting of initially drying 10 out the lining of a furnace which shall be available for protective purposes during subsequent operation of the furnace.

In practicing my invention, I provide a suitable furnace structure including an energizing or induction coil, a crucible located therewithin, electric-insulating material separating the coil from the crucible, and a star-like cage or basket immediately surrounding the crucible.

20 In the single sheet of drawings,

Figure 1 is a view, in vertical section, through an induction-furnace assembly embodying my invention,

Fig. 2 is a bottom plan view of the particular element embodying my invention, illustrated as located alone, and

Fig. 3 is a fragmentary view, on an enlarged scale, of the star-like cage element.

Referring more particularly to Fig. 1 of the drawings, I have illustrated a suitable outside casing 11 which is shown as consisting of metal but which may or may not be utilized. An energizing coil, designated by 12, comprises a plurality of turns of a suitable current-conducting wire or bar, shown as being substantially rectangular in lateral section, although the energizing coil forms no particular part of my present invention.

The space within the casing 12 is shown as 40 being partially filled by a suitable electric-insulating granular material 13 which may be zircon sand. A crucible 14, which may be of any suitable material, in accordance with the materials which are to be melted therein, 45 is located within the casing 11 and is supported by the granular electric-insulating material 13.

A pouring spout 16 is provided at the upper edge of the crucible 14, and suitable means, 50 not specifically illustrated in the drawings,

may be provided to permit of tilting the furnace in order to pour the metal out of the crucible after it has been melted therein.

It may be well to again call attention to the fact that the casing, the energizing coil and the crucible proper may be of any suitable or desired kind and do not constitute specific parts or elements of my present invention.

A star-like metallic cage or basket 17 is provided which is located outside of, and in direct operative engagement with, the crucible 14. The cage or basket 17 is preferably made of a non-magnetic steel and comprises an upper open ring or annular member 18 to which are connected a plurality of downwardly extending strips 19. The strips 19 are suitably riveted against the outer surface of the strip 18, as by a plurality of rivets 20, and it is one of the important elements of my invention to provide a plurality of relatively deep recesses 21 extending upwardly from the bottom edge of the strip 18, substantially as shown in Fig. 3 of the drawings. A substantially flat open annulus 22, also of metal, is provided at the bottom of the bent strips 19, the strips being riveted to the annulus 22 by a plurality of rivets 23, as is shown more particularly in Fig. 2 of the drawings. A substantially flat open annulus 22, also of metal, is provided at the bottom of the bent strips 19, the strips being riveted to the annulus 22 by a plurality of rivets 23, as is shown more particularly in Fig. 2 of the drawings. A substantially flat open annulus 22, also of metal, is provided at the bottom of the bent strips 19, the strips being riveted to the annulus 22 by a plurality of rivets 23, as is shown more particularly in Fig. 2 of the drawings. A substantially flat open annulus 22, also of metal, is provided at the bottom of the bent strips 19, the strips being riveted to the annulus 22 by a plurality of rivets 23, as is shown more particularly in Fig. 2 of the drawings.

Another important element of my invention is that each of the strips 19 at 75 that portion thereof, immediately adjacent to the outer peripheral edge of the member 22, are reduced in width, as shown at 24 in Fig. 2 of the drawings.

The cross section of each of the bars 19 80 should be such that

$$\frac{W}{B}$$

is less than 2. In this equation W is the width of each bar in centimeters, and

$$B = \sqrt{\frac{R}{4\pi P}},$$

R is the resistivity in electro-magnetic units 85 of the material used in the bars, and P is equal to 2π times the frequency. This ensures that the eddy current losses in the strips or bars 19 shall be below a predetermined value, so that the bars shall not be 100

excessively heated during normal operation of the furnace.

The sand 13 is rammed between the inductor coil and the cage or basket, as well as 5 between the inductor coil and the casing. The relatively narrow spaces between the bars 19 may be packed with ganister or other suitable material to prevent the escape of sand, in case the crucible is removed for 10 placement. The inside of the cage or basket may be coated with a suitable lining material, such as silica sand or magnesite, with or without a suitable binder, such as tar.

The cage 17 may be grounded, either to the 15 casing 11, if the same is of metal, or directly to a ground, the casing 11 being grounded as shown at 26 in Fig. 1 of the drawing, if of metal.

Upon the initial application of electric 20 energy to the inductor coil, heat is developed in the cage or basket by inductive effect, and the amount of energy translated into heat is made such that the lagging or lining materials are properly dried out. When the proper amount of drying out has been effected, 25 the restricted portions of the member 18 and of the individual bars 19 will be melted, because of the general heating up of the furnace, or the amount of energy provided at 30 the terminals of the coil 12 may be increased to make sure that proper melting of all of the restricted portions is effected. When the cage is thus opened, further generation of heat in the individual bars is reduced to a 35 very small amount.

It may be pointed out that the initial melting of metal in the crucible, particularly if it is of a metal or an alloy melting at a relatively high temperature, will effect sintering of the lining to form a hard or coherent furnace lining which may be easily broken out and replaced if and when injured or worn out during the operation of the furnace. The restricted portions of the cage or 45 basket may be provided in any part or parts thereof, and it is obvious that the separated elements of the cage or basket will act as a screen in the case of escape of molten metal through the wall of the crucible.

50 Various modifications may be made in the device embodying my invention without departing from the spirit and scope thereof and I desire therefore, that only such limitations shall be placed thereon as are imposed by 55 the prior art or are set forth in the appended claims.

I claim as my invention:

1. In an electric-induction furnace having a refractory lining and an energizing coil, 60 the method of drying the lining which comprises locating in the lining, during its construction, a distributed metallic cage within the coils and energizing the coil to effect heating of the metallic cage by induction, 65 whereby to effect drying of the lining.

2. In an electric-induction furnace having a refractory lining and an energizing coil, the method of drying the lining which comprises locating a star-like distributed metallic cage in the lining during its construction, energizing the coil to a predetermined degree to effect heating of the metallic cage by induction to effect drying of the lining and continuing said induction heating of the cage and the lining until the electric continuity 70 of the metallic cage is interrupted at a plurality of places.

3. In an electric-induction furnace having a refractory lining and an energizing coil, 75 the method of drying the lining which comprises locating a star-like distributed metallic cage in the lining during its construction, said metallic cage comprising a plurality of strips including a connecting portion of reduced area of cross section, energizing the coil to effect heating of the metallic cage by induction to effect drying of the lining and continuing the induction heating of the cage and of the lining until the electric continuity 80 of the cage is interrupted by the melting of the connecting portion of reduced area of cross section.

In testimony whereof, I have hereunto 85 subscribed my name this twenty third day of December, 1929.

NEVILLE RYLAND DAVIS.
